TEMPLE ROLL

Charles Thomas Dickey, Elizabeth, N. J.

Application January 4, 1939, Serial No. 249,207

3 Claims. (Cl. 139—296)

This invention relates to a roll for use in a loom temple.

As is well known to those skilled in the art, a loom temple is employed at each side of the loom adjacent the fell of the cloth being woven, for the purpose of uniformly maintaining the cloth stretched widthwise.

In connection with various types of fabrics, for example, as those composed wholly or largely of rayon or cellulose ester filaments as acetated cellulose, or those of a fine and delicate nature, it has long been customary to have the surface of the roll of the temple which engages the cloth composed of rubber or rubber composition.

But the pressure and pull of the cloth towards the center of the loom over the inner part of the temple acts to wear away the rubber surface of such a temple roll.

The small amounts of sulfur normally present in rayon made by the viscose process aided by frictional heat, appear to vulcanize or otherwise indurate the rubber and destroy its "life," while the "fumes" or products of an acid nature evolved from, or present in the artificial filaments employed, especially acetate filaments, have a direct solvent and deteriorating effect upon the rubber surface and consequent rapid surface smoothing and disintegration of said rubber.

The combined result is that the life of the roll is considerably shortened and the efficiency of its proper functioning correspondingly diminished. The amount of such wear depends upon various conditions other than above indicated, especially upon the particular type of fabric being woven and the material of which it is composed.

One of the objects of the present invention is to provide a construction of that type of temple employing a non-rubber body, in which the above indicated and other disadvantages are substantially non-existent, as will be herein more particularly pointed out.

Another object is to provide a temple roll having the initial desired frictional gripping surface, which remains uniform and substantially unimpaired for an indefinite period of time.

A third object is to provide a temple roll of required frictional gripping surface which is unacted upon and unimpaired by any of the components of, in, or evolved incident to the textile being woven.

A further object is to provide a temple roll wherein the surface passing in contact with the cloth, does not leave a mark or streak, or deposit material on the goods, as is the case where a rubber-faced roll is used, especially when the

rubber has been softened by the "fumes" from the filaments being woven. This is an important point because the goods are plain woven white and afterwards dyed. Even if an almost unnoticeable streak is left on the goods from deposition of tiny traces of rubber, this materially interferes with uniform penetration of dyestuff in the dyeing operation for the reason that rubber is absolutely insoluble in water, and the result is that uneven and unlevel dyeings result.

Other objects of the invention will appear more fully and clearly from the accompanying description and drawing, and will be particularly pointed out in the claims.

The general nature, function and purpose of a loom temple of the roll type are so well known and familiar to those skilled in the art, that it here only becomes necessary to illustrate a portion of one typical form of a temple, together with preferred forms of the invention embodied therein.

In the drawing and illustrative examples are shown and described several preferred forms of temple roll embodying my invention.

Fig. 1 is an end elevation of a temple head with the form of roll embodying the invention located therein;

Fig. 2 is a top plan view of the construction shown in Fig. 1;

Fig. 3 is a side elevation of the core forming the central part of the roll;

Fig. 4 is a face view of one of the units from which the roll is fabricated;

Fig. 5 is a side view of the unit shown in Fig. 4;

Fig. 6 is a longitudinal cross section through a fabricated roll in an intermediate stage of manufacture;

Fig. 7 is a longitudinal cross section through a finished roll.

The invention is shown in connection with the usual type of temple wherein two rolls are rotatively mounted. The temples are arranged in pairs, one at each side of the loom, and may be termed right-handed and left-handed since their function is to laterally stretch the cloth being woven to the right and left side of the loom. The construction of the temple is the same in both cases and therefore only a right-handed temple has been illustrated.

The form of roll embodied in the present invention is adapted for use in substantially all types of roll temples.

The temple illustrated in Figures 1 and 2 comprises an arm 1, of which only a portion is shown and by which it is mounted upon the loom at the

forward end, and a main body portion or pod 2 formed thereon having a trough-like shape in which the rolls are mounted. The temple rolls are journaled on pins 3 supported in the end walls of the pod 2, the inner ends 4 being fitted into the end wall 5 and the outer ends being provided with enlarged screw-threaded heads 6 which are tightly threaded into the end wall 7.

The temple roll 8, to perform its function of putting lateral tension on the cloth being woven, has its surface formed into alternating ridges 9 and grooves 10 arranged in the form of a helix. In constructing the roll 8, a tubular core 11 is provided having an enlarged head or flange 12 formed on one end and an internal bore 13 which acts as the journal on pin 3. The core 11 may be made of wood, impregnated and/or plasticized wood flour, wood pulp or the like.

The outer part of the roll 8 in which the ridges 9 and grooves 10 are later formed is fabricated or built up of a plurality of washer-shaped members 14 in which the outside diameter is slightly greater than that of the finished roll and the diameter of the hole 15 is slightly smaller than the diameter of the core 11.

To construct the roll 8, the proper number of impregnated washer-like members 14 are closely placed on the core 11 and extend from the flange 12 to the opposite end of the core. The core with its assembled members 14 thereon is then subjected to pressure or pressure and heat, in a device having dies with an internal configuration which will compress, distort, groove and furrow the substantially cylindrical shape of the series 35 of members 14 into the helically arranged ridges 9 and grooves 10 of the finished roll 8. During this operation the members 14 are so compressed and merged into one another that they form a highly resistant, substantially one piece unit having the characteristics desirable in a temple roll. The diameter of the flange 12 on the core 11 is less than the outer diameter of the roll 8 and hence does not come into contact with the cloth or fabric upon which the temple roll acts. By 45 this arrangement and construction the temple roll is only subjected to wear upon that part of itself which has the wear resisting qualities given it by the material from which the members 14 are composed.

The members 14 are preferably of woven natural or artificial fibers or admixtures thereof as cotton, linen, wool, silk or rayon, and impregnated with a thermoplastic body or bodies which are substantially unaffected by the fibers being woven, or materials contained therein or evolved therefrom. And conversely, solvents, non-solvents, diluents, softeners and plasticizing bodies used in conjunction with the impregnating material must be substantially devoid of solvent action 55 upon the filaments constituting the textile being treated.

Suitable impregnating bodies for this purpose are cellulose derivatives in the thermoplasticized condition as cellulose esters and ethers, or a 60 thermoplastic natural or synthetic resinous body or mixtures thereof, or a thermoplastic mixture of cellulose derivative and resinous body in proportions varying with the chemical composition and physical constants of the same.

In carrying the above method of my invention 70 into effect, I may take 4 pounds avordupois of ten ounce duck, drill or canvas, and permeate or impregnate the same with a resinous body of the vinyl type rendered fluid by solution in a volatile petroleum hydrocarbon mixture or other solvent

or solvent combination, preferably of such flowability as will thoroughly permeate the woven fibers with the minimum of solvent, excess of the latter after impregnation, being removed as by an evaporative step.

The canvas, after removal of volatile portion therefrom, weighs about 6 pounds 11 ounces avordupois. From this impregnated textile, washer-like members are cut as shown in Fig. 4.

Or the original textile may be cut into washer-like members which afterwards are impregnated in manner as above indicated or its substantial equivalent.

Example II.—In an alternative method, the woven fiber may be impregnated as in the previous example, using a cellulose derivative as an etherized cellulose, preferably of relatively high degree of etherification as, for example, highly ethylated ethylcellulose or highly benzylated benzylcellulose, or mixtures of the same, with suitable solvents and thermoplasticizing bodies if desired.

A plurality of such impregnated textile sheets are then stacked one upon the other, in number so that when pressed together into a unitary-appearing body, a slab of thickness to fit the length of 11 of Fig. 3 is formed.

The plurality of sheets are then compacted in any suitable manner.

The impregnated sheets after being compacted into a unitary block or slab of thickness approximating the length of the plurality of washer-like members 14 shown in Fig. 6, are then cut in a direction perpendicular to the long axis of the threads, so as to form unitary hollow cylindrical bodies with inner diameter nearly equal to the outer diameter of core 11 and of outer diameter substantially the same as 14, and in appearance will be the equivalent of 14 in Figure 6, except that the plurality of 14 on 11 in Figure 6, is replaced by a unitary member.

Compression and distortion is then applied as described in the previous example, to produce the equivalent of the finished temple roll shown in Figure 7.

Example III.—In another embodiment of my invention, fibers in the unwoven state but preferably in a twisted condition, are chopped to a fraction of an inch in length, then homogeneously intermingled with the suitable thermoplastic body in any effective way, being afterwards extruded in manner now known in the plastic art to form an endless shell which fits over core 11 and of diameter shown at 14 of Figure 6, after the volatile portion has been substantially removed, if evaporative solvents have been employed.

The shell of indefinite length is then cut to individual lengths to fit over core 11 (equivalent to the plurality of 14 shown in Fig. 6), one length placed over said cellulose or other suitable core, and finally compressed and distorted as shown in previous examples, or in a manner to produce an analogous result.

In the foregoing examples, after removal from the press, the helically arranged ridges 9 are more or less rounded from thermoplastic extruded thereon. The final operation is a grinding or abrasive treatment whereby 9 is smoothed until a flattened face is formed, as shown at 9 in Figure 7.

The plurality of woven or unwoven threads may be dyed, mercerized or otherwise treated before impregnation, and the impregnating medium may be colored as by addition of dyestuff or pigment.

The important feature of this invention resides in, and its efficiency depends upon, the relative percentage of raw edges of outwardly-projecting fibers constituting as the fabric-engaging surface the periphery of 14 of Figure 6, compacted and held together by a thermoplastic body not deleteriously affected by components in, or evolved from, the fibers or filaments passing over the same, and constituting the helically raised 10 ridges 9 of Figure 7, wherein the surface of 9 is substantially parallel with core 11.

What I claim is:

1. A roll for a loom temple comprising a wooden core having an internal shaft bearing; a hollow cylindrical body of twisted, unwoven cotton fibers concentric therewith and secured to said core; said fibers being rigidly encased in a matrix of thermoplastic cellulose derivative material not adversely affected by the textile being woven, 20 components contained therein or evolved therefrom; the fiber aggregates constituting an ex-

terior toothed or furrowed cloth-engaging and frictional-gripping surface of compacted, outwardly-projecting fiber ends.

2. A temple roll comprising a hollow core surrounded by and attached to a helically grooved hollow cylinder composed of fibers so arranged in a thermoplastic matrix of highly etherized cellulose ether which normally is solid, that the long dimension of said fibers is perpendicular to the axis of the core. 5

3. A roll for a loom temple comprising a core and a plurality of textile washer-like members previously impregnated with colloided highly etherized thermoplastic cellulose ether concentrically secured to said core; said washer-like 15 members being indistinguishably merged into a unitary-appearing, highly-resistant, cloth-engaging and frictional-gripping unit with helically arranged grooves and abraded ridges having outwardly-projecting fibers. 20
